UNITED STATES PATENT OFFICE.

AURA E. WHITEHEAD, OF DETROIT, MICHIGAN, ASSIGNOR TO FARRAND & VOTEY ORGAN COMPANY, OF SAME PLACE.

WINDING OR REWINDING MECHANISM FOR MECHANICAL MUSICAL INSTRUMENTS.

SPECIFICATION forming part of Letters Patent No. 683,717, dated October 1, 1901.

Application filed May 13, 1901. Serial No. 60,068. (No model)

To all whom it may concern:

Be it known that I, AURA E. WHITEHEAD, a citizen of the United States, residing at Detroit, in the county of Wayne and State of Michigan, have invented certain new and useful Improvements in Winding or Rewinding Mechanism for Mechanical Musical Instruments, of which the following is a specification, reference being had therein to the accompanying drawings.

The invention consists in the construction of the driving mechanism for the take-up and paper roll of a self-playing musical instrument; and it consists particularly in the construction, arrangement, and combination of the various parts, as more fully hereinafter described.

In the drawings, Figure 1 is a vertical section through one end of the tracker-board box, showing the winding and rewinding device in elevation. Fig. 2 is an enlarged section illustrating the drive-shaft and the clutch thereon. Fig. 3 is an elevation of the end of the tracker-board box, showing the device in elevation.

In the ordinary self-playing musical instrument the tracker-board, which is not shown, is ordinarily placed in a recess or box at the front of the machine. This box I refer to as the "tracker-board" box, one end of it being shown as the vertical board A in the drawings, the other end, which is not shown, being a similar vertical board, in which two boards are journaled the ends of the supporting-shaft of the take-up roll B, and in which boards are supported suitable stub-shafts, with which the ends of the paper-roll C may be detachably engaged.

D is the shaft of the take-up roll, which is journaled in the end boards of the tracker-board box, as shown in Fig. 1. On this shaft is a gear-wheel E, which meshes with a pinion F on the drive-shaft G and which is constantly driven by any suitable motor (not shown) and which is journaled in a box or bearing H in the lower end of the shifting bar I. This shifting bar is supported in a groove or guideway J in the outer face of the end board A of the tracker-board box. It is

provided with the slots a; through which project the screws b, which at once form holding means and a guide for the bar I. Upon the shaft G is a sprocket-wheel K, with which engages a sprocket-chain K', which likewise engages a sprocket-pinion L on the counter-shaft M. This counter-shaft is journaled in the bracket N on the end board A. The inner end of the shaft M is provided with a socketed head O to receive the pin or lug on the paper-roll C. On the sprocket-pinion L is a grooved hub b', with which is engaged a yoke c on the end of the rock-arm d, which projects from a rock-shaft e, journaled in the brackets h, secured on the end board A, as plainly shown in Fig. 3. Depending from the rock-shaft e is an actuating rock-arm i, the lower end of which is connected by the link k with an actuating-lever l, which projects up through a slot in the bottom of the tracker-board box.

In the position of the parts shown in Fig. 1 the drive-shaft G will rotate the pinion F, which is in mesh with the gear-wheel E, and will drive the take-up roll B, thus feeding the perforated paper over the tracker-board for the purpose of causing the machine to play in the well-known manner. If it is desired to rewind the perforated strip upon the paper-roll C, the operator shifts the lever l to the right, which through the connections described will rock the shaft e and the rock-arm c, sliding the sprocket-pinion L longitudinally upon its shaft M and causing a spur or pin m on the hub b to engage a corresponding spur or pin n on the collar o, fixed to the shaft M, thereby rotating the shaft M and driving the paper-roll C, causing the perforated sheet to wind thereon.

In order to simultaneously disengage the pinion F from the gear-wheel E, I provide the rock-shaft e with a rock-arm o', which engages a socket or recess r in the shifting bar I, which when the shaft e is rocked will press down the shifting bar I and with it lower the shaft G into the position shown in dotted lines in Fig. 1, moving the pinion F away from and clear of the gear-wheel E. The sprocket-chain K' is sufficiently slack

and the shaft G sufficiently long to permit of this motion of the shaft to disengage the pinion from the gear-wheel.

Upon the shaft M, I arrange a brake-wheel 5 Q, and I apply to this brake-wheel a spring-brake R, having constant engagement therewith. This brake acts to slightly retard the rotation of the paper-roll C, so as to put the necessary tension thereon between the rolls 10 C and B in its passage over the tracker-board.

This device, as will be seen, is exceptionally simple in construction, positive in operation, economical to build, and occupies but a very small space, the whole device being supported upon the end board A of the tracker-board box, so that it will always be in proper fixed relation to the rolls B and C, which are journaled in that board. Thus the shrinking 15 and swelling of the wood or even the racking 20 of the instrument will not in any way affect the position or operation of the motor and its drive mechanism or materially increase the friction thereon, which of course would increase the power of the operator to drive the 25 machine.

What I claim as my invention is—

1. In a self-playing device for musical instruments, the combination of a tracker-board box, the take-up roll journaled therein, the 30 paper-roll, a counter-shaft in one end of which the paper-roll is detachably engaged, a driven shaft, a pinion thereon, a gear-wheel on the take-up roll, a drive connection from the driven shaft, a loose wheel on the counter-shaft, a clutch between the loose wheel and 35 its shaft, a sliding bearing for the driven

shaft and an actuating-lever for simultaneously actuating the clutch and the sliding bearing for the purpose described.

2. In a winding and rewinding mechanism 40 for mechanical musical instruments, the combination of the rock-shaft e and an actuating-lever therefor, of the shifting bar I slidably supported in bearings on the tracker-board box beside the rock-shaft, a driven shaft G 45 journaled in said shifting bar and having a pinion adapted to be engaged and disengaged with the gear-wheel on the take-up roll, of the rock-arm o' engaging said shifting bar or rock-arm c, a sprocket-pinion l driven from the 50 drive-shaft G, the counter-shaft M on which said sprocket-wheel is loosely journaled, a grooved hub on the sprocket-wheel with which the rock-arm c engages and the clutch between the hub of the sprocket-pinion and the shaft M, substantially as and for the purpose described. 55

3. The combination with the tracker-board box of the take-up roll B journaled therein, of the end board A, the counter-shaft M journaled on the end board, the drive-shaft G journaled thereon, the rock-shaft e journaled in brackets supported on the end board and the winding and rewinding drive connections for the rolls B and C actuated from the rock-shaft e substantially as described. 60

In testimony whereof I affix my signature in presence of two witnesses.

AURA E. WHITEHEAD.
